FOLDING TABLE

Benedict E. Willett, Dayton, Ohio, assignor to
 Ferguson Brothers Manufacturing Company,
 Hoboken, N. J., a corporation of New Jersey

Application May 26, 1932, Serial No. 613,624

5 Claims. (Cl. 45—11)

This invention relates to a folding table and more particularly to a card table the legs of which fold against the table top.

One object of the invention is to provide improved mechanism for so connecting the several legs of the table that they will move in unison, thus causing all the legs to be operated when movement is imparted to one of them.

A further object of the invention is to provide such mechanism which will be simple in construction and can be produced and installed at a low cost.

A further object of the invention is to provide such a mechanism which will be of a strong durable character and in which the connections between the legs will not loosen or become slack due to long use.

Other objects of the invention will appear as the device is described in detail.

In the accompanying drawing Fig. 1 is a top plan view of a table embodying my invention, showing the legs folded; Fig. 2 is a bottom plan view of a portion of such a table showing a part of the actuating mechanism; Fig. 3 is a section taken on the line 3—3 of Fig. 2, looking in the direction of the arrows and showing the leg folded; Fig. 4 is a view similar to Fig. 3 showing the leg extended; Fig. 5 is a sectional view taken on the line 5—5 of Fig. 4; Fig. 6 is a section on the line 6—6 of Fig. 4; and Fig. 7 is a detail of one end of one of the links.

In the drawing I have illustrated one embodiment of my invention but it will be understood that this particular embodiment has been chosen for the purposes of illustration only and that the mechanism may take various forms without departing from the spirit of the invention.

In this particular embodiment of the invention the table comprises a table top 6 which is preferably rectangular in form and has flanges 7 depending from the respective edges thereof. The flat upper member of the top may be of thin inexpensive material and the flanges constitute a rigid supporting frame on which the legs and operating mechanism are supported. A leg 8 is mounted at each corner of the table for pivotal movement about an axis parallel with one of the flanges, so that the leg will fold against the table top within the flanges and parallel with the adjacent flange. Each leg is pivotally mounted on a bracket 9 having a part or flange 10 rigidly secured to one of the flanges 7 of the table top by means of a suitable attaching device, such as a screw 11. This bracket has an upper member 12 which extends inwardly from the flange to which the part 10 is connected and bears against the upper member of the table top but is not attached thereto. Extending downwardly from the respective sides of the upper part 12 of the bracket are parallel ears 13 and

14, the ear 14 bearing against the adjacent flange 7. The leg has an upwardly extending part which projects between the ears 13 and 14 and is pivotally connected therewith. As here shown, this connecting part is in the form of a sheet metal extension having a socket portion 15, which embraces one edge of the leg and is rigidly secured thereto, and having arms 16 extending beyond the end of the wooden part of the leg. These arms 16 are spaced apart such a distance that they will fit snugly between the ears 13 and 14 and a pivot pin 17 extends through the ears 13 and 14, through the arms 16 and is firmly seated in the flange 7 against which the ear 14 bears, thus serving not only to pivotally connect the leg with the bracket but to rigidly secure the bracket to the second flange 7. In the present instance, the pivot pin is in the form of a screw, the end of which is tapered and threaded to enter the flange 7. It will be noted that the pivot pin is spaced some distance from the top member 12 of the bracket for a purpose which will hereinafter appear.

A flexible connecting mechanism extends about the edges of the table within the flanges and is operatively connected with the several legs so that all the legs will be caused to move in unison. In the present arrangement, a bar 18 is slidably mounted on each flange 7, between the ends thereof, and is here shown as supported in clips 19 secured to the flange. This slide bar is of a length considerably less than the length of the flange and its ends are spaced from the ends of the flange. The several slide bars are connected one to the other by flexible members 20, here shown as flat metal tapes. Each flexible member is firmly secured to the ends of adjacent slide bars and extends about a guide roller or pulley 21 which is rotatably supported on the top member 12 of the bracket 9 and is arranged between that member and the pivot pin 17. Each slide bar, is operatively connected with one of the legs 8 by means of a link 22 which is pivotally connected at one end with the leg and at its other end with the slide bar so that each bar and its connected leg will move in unison. In the present construction, each slide bar has an intermediate part 23 bent inwardly and offset from the flange on which the bar is slidably supported. This offset portion of the slide bar is provided with an aperture 24 and the adjacent end of the link 22 is bent toward the flange and has its end portion reduced in width and provided with a finger 25, which extends in the direction of the length of said link but is offset therefrom. When the link is positioned at an angle to the plane of the bar the finger may be inserted through the aperture 24 and when the link is moved to its normal position, substantially parallel with the slide bar, and connected with the leg the finger

25 will overlap the bar beyond the aperture and thus pivotally connect the link with the slide bar. This construction not only provides a connection which may be very quickly and easily established but also provides a connection which will not loosen with wear. It will be apparent, therefore, that the several legs are so connected one with the other that when movement is imparted to one leg, to fold the same or to move it to its open position, a like movement will be imparted to all the other legs. The metal tapes will not stretch and the several parts are so mounted that they will be held firmly in their proper positions and will not loosen by wear. None of these parts are carried by the thin top member of the table and therefore the operation of the device will not be affected by warping or distortion of this top member.

Preferably a lock is provided for holding the legs positively in their extended positions and, in the present construction, a bar 26 of resilient metal is rigidly secured at one end to one of the flanges beneath and parallel with the slide bar 18 which is supported on that flange. At its other end this locking bar has an upwardly extending lug 27 which normally rests on the surface of the adjacent slide bar but which is so arranged that when the legs are moved to their extended positions the lug will enter a notch 28 in the slide bar and will thus firmly hold the slide bar against movement in either direction and will consequently lock all the legs in their extended positions. Any suitable means may be provided for actuating the locking bar to release the operating mechanism and legs, and, in the present instance, a plunger 29 is slidably mounted in the flange at a point between the ends of the locking bar and has its inner end connected with, or arranged to engage, the locking bar 40 while its outer end is exposed on the outer side of the flange so that it may be actuated to press the locking bar inwardly and disengage the lug from the slide bar. As here shown, the inner end portion of the plunger is reduced in diameter and extends through an opening 30 in the locking bar. The end of this reduced portion is upset or enlarged at 31 to retain the same in the opening and a washer 32 is mounted on the reduced portion between the locking bar and the outer portion of the plunger, thus confining the bar between the enlarged end of the plunger and the washer.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. A folding table comprising a rectangular table top, a flange depending from each edge thereof, a leg pivotally mounted at each corner of said table top, a guide roller mounted at each corner of said table top for rotation about a vertical axis, a bar extending lengthwise of and slidably mounted on each of said flanges, flexible members extending about the respective guide rollers and connected with the adjacent bar to cause said bars to move in unison, each of said bars having an intermediate portion offset from its supporting flange and provided with an aperture, a link having a laterally extending end portion provided with a finger adapted to be inserted in said aperture when said link is in one position

and to extend beyond said aperture when said link is in another position, and means for connecting the other end of said link with one of said legs when said link is in the last mentioned position, one of said bars having a locking recess, a resilient locking bar having one end secured to the flange on which said recessed slide bar is mounted and having at its other end a projection bearing normally on the face of said slide bar and so arranged that it will enter said recess when said legs are moved to their extended positions.

2. A folding table comprising a rectangular table top, a flange depending from an edge thereof, legs pivotally mounted at each corner, a bar slidably mounted on said flange and having a locking recess, a resilient locking bar having one end secured to said flange and having at its other end a projection bearing normally on the face of said slide bar so arranged that it will enter said recess when said bar is moved to one of its extreme positions, and a link connecting said bar with said leg.

3. A folding table comprising a rectangular table top, a flange depending from each edge thereof, a leg pivotally mounted at each corner of said table top, a guide roller mounted at each corner of said table top for rotation about a vertical axis, a bar extending lengthwise of and slidably mounted on each of said flanges, flexible members extending about the respective guide rollers and connected with the adjacent bars to cause said bars to move in unison, means for operatively connecting said slide bars with the respective legs, one of said slide bars having a locking recess, a yieldable locking member mounted on the flange which supports said recessed slide bar and having a projection which bears normally on the surface of said slide bar, said projection being arranged to enter said recess when said legs are moved to their extended positions.

4. A folding table comprising a rectangular table top, a flange depending from each edge thereof, a leg pivotally mounted at each corner of said table top, a guide roller mounted at each corner of said table top for rotation about a vertical axis, a bar extending lengthwise of and slidably mounted on each of said flanges, flexible members extending about the respective guide rollers and connected with the adjacent bars to cause said bars to move in unison, means for operatively connecting said slide bars with the respective legs, one of said slide bars having a locking recess, a yieldable locking member mounted on the flange which supports said recessed slide bar and having a projection which bears normally on the surface of said slide bar, said projection being arranged to enter said recess when said legs are moved to their extended positions, and a device mounted on said flange to actuate said yieldable locking member and move said projection out of said recess.

5. A folding table comprising a rectangular table top, flanges depending from the edges thereof, legs pivotally mounted at each corner, a member mounted to slide in parallelism with a flange and having a locking recess, a spring actuated locking element secured to said flange and having an end projecting for engagement with the recess of said slide member to act as part of a locking means for holding the legs in extended position, and linkage connecting said slide member with a leg.
